UNITED STATES PATENT OFFICE

GEORGE S. MALCOLM, OF AUBURN, CALIFORNIA

DISPLAY CARD HOLDER

Application filed December 28, 1931. Serial No. 583,443.

This invention relates to devices for holding display cards and particularly to one especially designed to hold the price cards or tags in connection with shelves on which merchandise is displayed for sale, as for instance in the so-called self-help groceries and similar retail stores.

The principal object of my invention is to provide a device for the purpose by means of which the cards or tags will be rigidly held against the front of the shelf in such a manner that while they are fully visible to the purchaser they are not in the way of and will not be disturbed by the withdrawal of any article from the shelf. The holders are also constructed so that the cards or tags may be easily placed in position, removed, or adjusted at any point along the shelf. The alteration or rearrangement of the price tags necessitated by changes in the prices of the goods or the rearrangement of the same on the shelves, may be easily effected by the clerks. The device is also extremely neat in appearance and forms a permanent attachment to the shelves which need never be disturbed and which is not in the way even if it is not actually being used.

At the same time the devices can be applied to the shelves without making any changes to the latter or removed without leaving any scars or visible indication of their previous use.

Also, any size price tags or other cards, or special signs, can be held by my device with equal facility.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Fig. 1 is a fragmentary perspective view of a store shelf arrangement showing my improved price card holders mounted in connection therewith.

Fig. 2 is an enlarged cross section of a holder as mounted on a shelf.

Fig. 3 is a bottom plan view of a holder attached to a shelf.

Referring now more particularly to the characters of reference on the drawing, the numeral 1 denotes a merchandise supporting shelf on which the goods 2 of various kinds are supported in segregated order as usual and as indicated in Fig. 1.

The card holder for any one shelf comprises a strip 3 extending lengthwise of and under the shelf adjacent its forward edge. Said strip has an upstanding lip 4 along the entire length of the same which extends in front of the front edge of the shelf and overlaps the lower portion of said edge. The holder strip and lip are preferably formed integral with each other and may be made of wood, metal or other suitable material; and may be made of a length to extend the full length of any shelf between its vertical partitions or supports, or in a number of sections for each shelf.

Each strip 3 is held in close but non-binding engagement with the bottom surface of the shelf by means of screws 5 projecting through slots 6 cut through said strips at spaced intervals in its length, and secured in the shelf from underneath. The screw heads 7 engage rigid plates 8 which cover the slots and engage the adjacent area of the underside of the strip 3 surrounding the slots. Said plates preferably have upstanding flanges 9 at their back edges engaging the back edge of the strip 3 so that said plates cannot turn.

The flanges also bear against the bottom of the shelf, so that the plates, and consequently the screw heads, are prevented from binding the holder strip.

The strip is therefore mounted for sliding movement transversely of the shelf and is normally retracted, so that the lip 4 is frictionally pressed against the front edge of the shelf by springs of any suitable type, mounted of course under the shelf. In the present instance the springs 10 are shown as being of the flat leaf type, extending lengthwise of the holder and disposed in the slots 100

6. One end of each spring bears against the back side of the corresponding screw while the opposite end is tightly fitted in a slit 11 in the holder strip at one end of the slot. As stated, any other suitable type of spring may be used for the purpose as long as it functions to pull the lip 4 against the shelf. The form shown however has the advantage of simplicity of construction and the springs 10 remain in their proper place in the holder when the latter is installed or removed, and are concealed and protected by the plates 8.

By means of this arrangement it will be seen that any number of price cards or tags 15 12 of equal thickness may be supported by any one holder at whatever position in the length of the shelf may be desirable, the lower edges of the tags being firmly gripped between the lip 4 and the front edge of the 20 shelf. To insert or remove any tag it is only necessary to engage the back of the holder with the fingers and pull outwardly, so that the resistance of the springs is overcome and the lip is moved away from the 25 shelf so as to disengage the tags. Only a slight movement of the holder is necessary to effect the release of the tags so that if it is desired to replace one tag the others in the same holder will not be displaced or fall out.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. In combination with a shelf, a card holder mounted in connection with said shelf and including a lip extending lengthwise of the shelf and overlapping the front edge of the same, means movably mounting said holder on the shelf and resilient means coacting with the first mentioned means maintaining said lip in pressing engagement with said shelf edge.

2. A card holder for use in connection with a shelf including a lip to extend lengthwise of the shelf and overlap the front edge of the same, a strip rigid with the lip and adapted to project under the shelf, means to support said strip against the under side of the shelf for movement transversely thereof, and spring means acting on the strip to hold the lip against said shelf-edge.

3. A card holder for use in connection with a shelf including a lip to extend lengthwise of the shelf and overlap the front edge of the same, a strip rigid with the lip and adapted to project under the shelf, strip support-

ing screws adapted to be mounted in and to depend from the shelf, said screws projecting through longitudinally spaced slots in the strip and arranged to permit of transverse movement of the strip relative to the shelf and screws, and springs between said screws and strip and acting on the latter to pull the lip against the front edge of the shelf.

4. In combination with a shelf, a card holder mounted in connection with said shelf and including a lip extending lengthwise of the shelf and overlapping the front edge of the same, a strip rigid with the lip and projecting under the shelf, strip supporting screws mounted in and depending from the shelf, said screws projecting through longitudinally spaced slots in the strip and arranged to permit of transverse movement of the strip relative to the shelf and screws, and flat springs extending lengthwise of the strip; said springs being disposed between the top and bottom surfaces of the strip and secured at one end to the strip and at the other end projecting into the slots and engaging the sides of the corresponding screws opposite to the front edge of the shelf.

5. A card holder for use in connection with a shelf including a base member adapted to lie against one face of the shelf, a lip on said member adapted to overhang the front edge of the shelf, means to mount said member on the shelf for movement transversely thereof, and means acting on the member to move the same transversely of the shelf in a direction to yieldably hold the lip against said edge of the shelf.

In testimony whereof I affix my signature.

GEORGE S. MALCOLM.
